UNITED STATES PATENT OFFICE

OSCAR W. FOX, OF FOREST HILLS, NEW YORK, ASSIGNOR TO GEO. BORGFELDT & CO.,
OF NEW YORK, N. Y., A CORPORATION OF NEW JERSEY

DESIGN FOR A SIPPER

Application filed December 7, 1932. Serial No. 46,317. Term of patent 7 years.

To all whom it may concern:

Be it known that I, OSCAR W. FOX, a citizen of the United States, and a resident of Forest Hills, county of Queens and State of New York, have invented a new, original, and ornamental Design for a Sipper, of which the following is a specification, reference being had to the accompanying drawing, forming a part thereof.

Fig. 1 is a front view of a sipper, showing my new design and showing an elongated hollow stem at the top of which is a decorative flower with a small hole contained therein.

Fig. 2 is a top plan view of the sipper illustrated in Fig. 1.

I claim:

The ornamental design for a sipper, as shown and described.

OSCAR W. FOX.
